UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

FOLDING MACHINE.

Application filed July 2, 1921. Serial No. 482,034.

To all whom it may concern:

Be it known that we, LEON E. LA BOMBARD and MELVIN H. SIDEBOOTHAM, citizens of the United States, and residents of Chelsea, in the county of Suffolk and State of Massachusetts, have invented certain new and useful Improvements in Folding Machines, of which the following is a specification.

10 This invention relates to the manufacture of paper receptacles such as envelopes, bags or boxes, and has particular reference to machines for folding flat blanks on two parallel lines and gluing together overlapped 15 edge portions thereof.

A particular object of our invention is to provide a box folding machine which, although employing no upper blank-forwarding belts, ensures complete control of the 20 blanks during their continuous travel from one end to the other without liability of any of the blanks turning askew.

Another object of our present invention is to provide an improved belt folder structure which will enable the belts to be slipped off from their driving and guiding pulleys when need for removal occurs, without disconnecting any parts of the machine.

Another object is to provide means for 30 adjusting the angle of those portions of the folding belts which effect the first folding operation upon the blanks.

Another object is to provide improved means for adjusting the vertical plane of 35 the mid-lengths of the operative stretches of the folding belts, to vary the distance of said belts from the fold or crease lines of the blank to best suit the character of the blanks being operated upon.

40 Another object is to provide means for effecting the various required adjustments of the machine without requiring wrenches or other tools.

With these and other objects in view, the 45 invention consists in the construction and combination of parts substantially as hereinafter described and claimed.

Of the accompanying drawings:

Figure 1 is a longitudinal sectional view 50 of a machine which includes our present improvements.

Figure 2 is a plan view of that portion of the machine which first acts upon the blanks, the broken line 1-1 and adjacent arrows

indicating the direction of view for Figure 55 1.

Figure 3 is a perspective view of the parts shown in Figure 2.

Figure 4 is a perspective view of the parts at the delivery end of the machine. 60

Figure 5 is a sectional view of the adjustable mounting of one of the folding belt driving pulleys.

Figure 6 represents a detail section on line 6-6 of Figure 1, on a larger scale. 65

Figure 7 represents a section on line 7-7 of Figure 2, on a larger scale.

Figure 8 is a sectional perspective view of one of the adjustable sleeve rolls for acting on the folded edges of the blanks. 70

Figure 9 represents a section approximately on line 9-9 of Figure 7.

Similar reference characters indicate similar parts in all of the views.

Portions of side members of the frame of 75 the machine are indicated at 12, said side members being connected by suitable tie rods. Two of the tie rods 13, 14, (see Fig. 1 near the left hand end and near its mid-length) serve the additional purpose of aiding to support certain parts of the machine hereinafter described.

Mounted on transverse screw rods 15, 15, so as to slide on one and be adjusted by the other, are brackets or castings 16 (Figs. 1, 2, and 3) which support two forwardly extending bars 17. The latter support two series of inclined frames 18 having rolls 19 which bear on blanks advanced from suitable feeding mechanism by the carrier belts 27 presently referred to. As the parts of the machine from the screw rods 15 to the rolls 19 are substantially the same as described and claimed in our application filed Sept. 30, 1920, Serial No. 413,841, a further 95 description thereof herein is unnecessary.

We will now describe the means for supporting the two carrier belts 27 in laterally adjustable positions. At the entrance or feed-supply end of the machine is a frame 100 or casting 20 for each of said belts, said frame being mounted on the tie rod 13 and on a screw rod 21. For the other end of each belt a frame or casting 22, which is also a gear case as hereinafter described, is 105 mounted on the tie rod 14 and on the drive shaft 23 and on a screw rod 24.

Each of the two frames or castings 20

is laterally adjustable by its own pair of screw rods 21, 24. Said screw rods are in alinement as indicated in connection with the rod 24 in Figure 4. Such mechanism 5 is well known for effecting lateral adjustment and is not claimed herein. It is quite generally employed when it is desired that one side of the mechanism shall be capable of adjustment independently of the other 10 side.

The two rods 15, 15, are not operatively connected in any way, and therefore each may be rotated by any suitable means without affecting the other.

15 Bolted to the frames 20, 22, are two longitudinal frame bars 25 having rolls 26 on which the carrier belts 27 run, suitable means such as small plates 26' being employed for laterally guiding the belts.

20 Each belt 27 is mounted at one end on an idle pulley 28 (Fig. 1) mounted in a frame 20 and at the other end on an idle pulley 29 supported in brackets carried by a frame 22, and is held taut by suitable tightener 25 pulleys 30, 31.

We have found in practice that the carrier belts 27 keep a better control on the blanks if said belts, instead of being driven by end pulleys, are operated upon by driving mechanism at a point intermediate their ends. Therefore we effect the drive of each belt by having its lower stretch pass between a drive wheel 32 carried by the shaft 23 and a wheel 33 so mounted that the belt 35 is yieldingly pinched between the wheels 32, 33 (Fig. 4). The shaft 34 of wheel 33 passes through an opening in the wall of the frame or gear case 22 and carries a gear 35 meshing with a gear 36 adjustable 40 longitudinally on and rotated by the drive shaft 23. The shaft 34 is mounted in the yoke arms of an elbow lever 37 pivoted at 38 and having its short arm pivotally connected to a fork 39 having a threaded shank 45 40 slidably mounted in an opening in the lower part of the casting 22. A hand wheel 41 having a nut hub engages the threaded shank, a set nut 42 being employed to hold the member 41 in adjusted position. A 50 spring 43 between the nut hub and the wall of the casting 22 acts, through the shank 40, its fork 39, elbow lever 37 and shaft 34 to cause the wheel 33 to bear on the lower or return stretch of the carrier belt with sufficient yielding pressure to pinch the belt 55 tightly between the wheels 33, 32 both of which, due to the intermeshing gears 35, 36, are driven by the shaft 23.

Owing to the drive of each of the carrier 60 belts as described, and the mounting thereof on wheels or pulleys and rolls all of which are supported or carried by members located at one side of the belt with nothing at the other side to obstruct bodily removal 65 of the belt at any time, much time is saved

when occasion arises for effecting such removal. As shown by comparing Figures 1, 3 and 4, there is a clear space between the inner edges of the two carrier belts 27, all of the wheels or pulleys and rolls being so 70 supported that either belt 27 can be slipped off into said clear space for removal, and after repairing or other treatment can then be returned, or another one substituted for it by slipping it edgewise over or onto said 75 pulleys and rolls.

As hereinafter explained, either of the 80 belts 44 can also be removed or replaced without disconnecting any parts of the machine.

By means of the independent screw rods 21, 24, each pair of which may be simultaneously rotated by a chain and sprocket wheel mechanism well-known and not necessary to illustrate, either or both of the 85 two carrier belts and their driving and supporting members just described may be laterally adjusted to suit different sizes of blanks to be folded.

Owing to the clear space between the 90 pulleys and belts of the two laterally adjustable frames 20, 22, 25, said frames may be adjustable into such close relationship as to operate upon the smallest sizes of box 95 blanks.

Of two prior types of machines of this 100 general character, one employs belts so twisted as to first turn up or "break" the blanks on their crease lines and then fold the up-turned portions in and down. Such machines as heretofore constructed are not capable of having the belts adjusted so as to engage the blanks at the proper distance from their crease lines for the first turning up or "breaking" of the blanks except to a quite limited degree. The other type referred to has inclined rods or bars which effect the first turning up or "breaking," and said rods or bars can be adjusted. But, since the said inclined members are stationary, the friction of the blanks thereon sometimes causes the blanks to turn askew which, of course, prevents proper folding on straight lines. Such inclined members 110 also often cause objectionable marks to appear on the folded boxes. In both types of prior machines it has usually been found necessary to employ upper driven carrier belts. In our present machine we dispense entirely with upper carrier belts and therefore all parts of the entire machine are 120 readily accessible for any kind of attention. The bars 17, frames 18 and rolls 19 ensure such frictional contact of the blanks with the two carrier belts 27 as to ensure straight travel of the blanks. This result is facilitated by the fact that no stationary "breaker" bars are employed. In the present machine the first turning up or "breaking" 125 of the blanks is effected by the same

130

belts as those which do the final folding, and the portions which effect such "breaking" are so universally adjustable as to operate properly upon any width or shape of blank of any kind of material used for paper boxes. The mechanism for effecting these adjustments will presently be described.

Each of the breaking and folding belts 44 is mounted at its far or delivery end (Figs. 1, 4 and 5) on a driving pulley 45 carried by a short stud shaft 46 mounted in bearings at the upper end of a casting or frame 22 and extending inwardly therefrom and having a sprocket wheel 47 connected by a sprocket chain 48 with a sprocket wheel 49 adjustable on and rotated by the drive shaft 23. The bearing for each of the shafts 46 is adjustable as hereinabove described to raise or lower the pulley 45. Each belt 44 at its end where the blanks are fed to the machine, is mounted on a pulley 50 (Figs. 2 and 3) idly mounted on a stud or pin carried by and projecting inwardly therefrom a bracket 51 adjustably clamped on the round outer end 52 of a socketed rod 53 slidable on the square or angular end 54 of a rod secured in an arm 55 having a hub 56 pivotally mounted on a vertical sleeve 57 formed as a part of a bracket 58 secured to one of the bars 25 (see Fig. 7). The hub 56 is clamped in position, when the arm 55 and the parts carried thereby are swung out or in (see full and dotted lines in Figure 2), by any suitable means such as a wedge 69 operated by a hand wheel 59 (Figs. 3, 7 and 9). The wedge 69 is mounted to shift endwise in a recess or bearing in the hub 56 and has a stem 69' threaded at its outer exposed end. The wheel 59 is internally threaded to fit the threaded end of the stem 69' so that, by rotating the wheel in one direction it acts as a nut to draw the wedge in a direction to bind against the stationary sleeve 57 and thereby secure the hub of the arm 55 in the desired vertical position or the desired position in or to which said arm has been swung laterally. Upon loosening the nut wheel 59, the arm can be swung or shifted vertically to the desired new position, after which the said nut wheel will be again tightened.

Idly mounted on a vertical pin 60 rising from the bracket 58 is a pulley 61 having a single flange 62. The pin 60 is not straight from end to end, its upper end being slightly bent or tilted (Fig. 7). On this bent or deflected portion is mounted a sleeve 63 and the pulley 61 is idly mounted on said sleeve. The lower or vertical portion of the pin 60 is mounted in the bracket sleeve 57 and is held in rotatively and vertically adjustable position by

suitable means such as a set screw 64. By changing the rotative position of the pin 60 its upper end can be inclined so as to tilt the pulley 61 and cause its face to guide that portion of the belt 44 running over it in either a vertical plane or slightly inclined inward or outward to best suit the particular blanks to be folded. And by adjusting the pin 60 vertically the pulley 61 is necessarily vertically adjusted so as to cause that portion of the belt to act on portions of the blanks at a greater or lesser distance from their crease lines.

As indicated by the full and dotted lines in Figure 2, the portions of the belts 44 which effect the first folding or "breaking" operation on the blanks can be caused to act at greater or lesser distances from the crease lines of the blanks. This is an important feature of our invention for the following reason:— Boxes are made of material differing widely as to thickness and stiffness. To properly effect the action of "breaking" on their crease lines, the distance from the crease lines to the points where picked up by the breaking means needs to be varied according to the character of the blanks, to obtain the proper leverage and to avoid opportunity for the parts being turned up or broken to buckle. So, for instance, the arms carrying the pulleys 50 are set in swung out position for thick stiff blanks, and are set in inner positions for thin flexible blanks. The height of each pulley 61 is varied for the same reason. That is, the portion of each belt 44 running from pulley 50 to pulley 61 should act on the blank at a greater or lesser distance from the crease line according to the character of the blanks. As has been explained, the hub 56 of the arm 55 can be shifted up or down on the sleeve 57 and clamped in vertically adjusted position by the wedge 69. Since the arm 55, by means of its extension members, carries the pulley 50 (Figs. 2 and 4), such adjustment of the arm adjusts the vertical position of that portion of the belt 44 which first acts on the blanks, said portion being that which runs from pulley 50 to pulley 61.

Each belt 44 is kept under proper tension by a spring 65 (Fig. 7) interposed between the bottom of the socket in rod 53 and the end of the rod 54.

Each belt 44 can be readily slipped off from, or returned onto, its pulley 50 at one end (Figs. 2 and 3), and its pulley 45 at the other end (Figs. 1 and 4) because all of said pulleys are supported or carried by members located at the outer sides of the belts with nothing at the inner sides to obstruct such removal or replacement. This also enables the folder belts 44 to be brought into close relationship (when the side halves

of the machine are adjusted close together) for the same purpose as explained in connection with the carrier belts 27.

For a purpose hereinafter explained, the pulley 45 at the delivery end of each belt 44 is adjustable. To this end (see Fig. 5) the shaft 46 is mounted in a bushing 66 which, in turn, is mounted in an eccentric sleeve bearing 67 having a handle 68 by which it is rotatively adjustable in its mounting in the casting 22 to vary the vertical height of the axis of rotation of the shaft and its pulley.

The amount of twist of that portion of each belt running from a pulley 50 toward a pulley 61 is varied by rotatively adjusting the bracket 51 on the round outer end 52 of the extension 53, thereby varying the inclination of the axis of the pulley 50. For some kinds of blanks, especially those made of heavy material, it is desirable that the twisted portion of the belt just referred to shall be incapable of yielding outwardly. To this end we support said portion by a twisted backing strip 70 connected at one end to a block 71 carried by an arm 72 extending from the sleeve 63. The other end of the strip 70 bears on the face of a block 73 carried by bracket 51, (Fig. 2) said block having a pin 74 engaging a slot 75 in the outer end of the strip 70. Said strip is of material sufficiently flexible to be twisted more or less to substantially conform to the amount or degree of twist of the belt 44 when the bracket 51 carrying the pulley 50 is rotatively adjusted to vary the inclination of the axis of rotation of said pulley 50.

Such adjustment of the degree of twist of the belt 44 necessarily also adjusts the twist of the strip 70 to a substantially corresponding degree, owing to the manner of supporting the said strip at its ends as just described.

The portion of each folding belt 44 beyond the pulley 61 continues in a twisted direction and runs over guiding pulleys adjustably mounted on a longitudinal rod 76 secured in blocks 77 supported by bar 25. Said guiding pulleys are indicated at 78, and the studs or pins on which they rotate freely are adjustably mounted in brackets 79 which, in turn, are rotatably and longitudinally adjustable on the rod 76. By these adjustments of the pulleys 78 the portion of either belt 44 beyond the pulley 61 can be caused to travel in any one of a wide variety of paths to suit the particular kind of blanks being operated upon.

As clearly shown in the drawings, the screws employed for securing the brackets 79 on the rods 76 and for securing the pulley studs in the brackets have wing portions by which they may be manually operated directly without the employment of a wrench or other tool. Therefore, when it is neces-

sary to effect an adjustment, no time is spent looking for or picking up a tool or adjusting a wrench. This is true also of all other parts of the machine as illustrated, each clamping or holding device having its own manually operable part not requiring a tool to operate it.

On each rod 76 is also adjustably mounted a double-flanged pulley 80 (Fig. 2) to guide the return or inoperative stretch of the adjacent folding belt 44.

To prevent the belts 44 from being deflected outwardly, such as by the resistance to folding of blanks made of heavy material, side guides 81 may be employed (Figs. 2, 4 and 6). Said guides are illustrated as strips suitably secured to the bars 25 but, obviously, they might be integral therewith.

In the operation of the machine as so far described, the blanks are successively supplied at the point α (Fig. 1) by suitable feed mechanism such as disclosed in our application filed June 20, 1921, Serial No. 478,846, and are carried forward by the belts 27, the bodies or middle portions of the blanks being held down, close to their usual longitudinal crease lines, by the inclined frames 18 and their rolls 19. As has been described, the arms 55, 53 are capable of being swung and fixed in adjusted positions so as to cause those portions of the belts 44 which travel from the pulleys 50 to the pulleys 61 to move in planes more or less laterally and vertically inclined to suit the particular blanks to be "broken" and folded. As the blanks travel, their outer or flap portions are turned up, and as they continue to travel beyond the location of the upright pulleys 61, said flap portions are folded in and their edges overlapped just before the blanks reach the delivery ends of the belts 27, 44 (Fig. 4).

It is to be understood, of course, that the edge portion of each blank carries a stripe of glue. The present drawings illustrate no gluing mechanism for the reason that in the complete machine of which the present drawings illustrate only the folding mechanism, the gluing mechanism is located within the area of the feeder as illustrated in our said application Serial No. 478,846.

We will now describe the parts of the present machine which frictionally engage the folded boxes and carry them to the pressing rolls 109, 111, hereinafter described.

As the folded blanks leave the belts 27, 44, they pass between upper and lower belts 82, 83 (Figs. 4 and 1) which are so located laterally, and are of sufficient width, to frictionally engage mid-width portions of the folded blanks, and carry them along. By suitable driving connections not necessary to illustrate the belts 82, 83, travel faster than the carrier and folder belts, for

a reason explained hereinafter. At their far or delivery ends the belts 82, 83, are mounted on pulleys 84, 85, respectively, said pulleys being laterally adjustable on drive shafts 86, 87.

An upper frame 88 is mounted on a screw shaft 89, and connected to the frame at 90 is an arm 91 of a collar which is connected to the hub of pulley 84 so that, when the screw shaft 89 is rotated to laterally adjust the frame 88, the pulley is correspondingly shifted along its drive shaft 86. Extending from the other end of the frame 88 and connected thereto by a slot and bolt to permit it to be adjusted outwardly to tighten the belt 82, is an arm 92 carrying a pulley 93 for the inner or receiving end of said belt. A hook 94 extends from the frame 88 over the upper stretch of the belt 82 to retain the belt on the pulleys which have no outer flanges. A roll 95 carried by a spring-pressed frame 96 pivotally connected to the frame 88 at 97, bears on the lower stretch of the belt 82.

A lower frame 98 is mounted on a screw shaft 99, and connected to the said frame at 100 is an arm 101 of a collar which is connected to the hub of pulley 85 so that, when the screw shaft 99 is rotated to laterally adjust the frame 98, the pulley 85 is correspondingly shifted along its drive shaft 87. An arm 102 having a pulley 103 for the inner or receiving end of the belt 83 is pivotally supported by, and longitudinally adjustable upon, a fulcrum 104. A spring 105 is connected to the arm 102 to hold it yieldingly in a position determined by an adjustable stop screw 106, thereby enabling the pulley 103 to yield when a folded blank enters between the upper and lower belts. A hook 107 extends over the lower stretch of the belt 83 to retain the belt in its pulleys.

When the blanks emerge from between the belts 82, 83, they pass between upper and lower driven shafts 109, 110, (Figs. 1 and 8). The upper shaft is preferably of uniform diameter so that any portions thereof may cooperate with a pair of sleeve rolls 111 having splined connection with the shaft 110, to compress or squeeze the sides of the folded blanks where they have been folded to render the fold permanent by reducing the tendency of the folded blanks to spring open in case the glue has not set sufficiently for the purpose. Owing to the coaction of the rolls 111 with the shaft roll 109 the margins where the blanks are folded on their crease lines are subjected to such pressure that the belts 82, 83 are not required to act as pressers but only to deliver the blanks to said rolls 111, 109. Each sleeve roll 111 has a groove 112 engaged by a yoke 113 having a hub or sleeve portion 114 mounted on a transverse rod 115 and adapted to be se-

cured in position along said rod by a screw 116. As stated, there are two of the sleeve rolls 111. For operation the rolls 111 are adjusted along the shaft 110 to positions where the folded blanks will pass with their folded edges between said sleeve rolls 111 and shaft roll 109, the intermediate portions of the folded blanks, which include three thicknesses of material due to the lap seam, passing through the wider space existing between the roll 109 and the portion of the shaft 110 intermediate the two rolls 111.

As is customary in machines of this type (see Figs. 1 and 6) long tapering strips or shoes 117 extend far enough under those portions of the folder belts to guide the partially folded blanks, one of which is indicated at *a* in Figure 6, and hold them in contact with the carrier belts 27 during a portion of their travel. As shown in Figure 6, one corner of each folding belt is bevelled. This is to enable the surface of the belt which acts on the blanks during their passage along the shoes 117 to bear flatwise upon the in-turned flaps of the blanks and to press the extreme angle or fold thereof. To facilitate an understanding of the reason for this feature of the invention, it may be imagined that a cross-section of the belt 44 represented a rectangle instead of as in Figure 6. In that case the upper right hand corner bearing against the side guide 81 and the lower right hand corner which would then bear on belt 27, would cause the belt 44 to be laterally bent or curved so that it would not press on the extreme angle or fold of the blank.

The operation of the machine is as follows:

Blanks are fed to the machine at the point *a* in Figure 1 as close together as their front and rear edge formations will permit. As they are carried along by the coaction of the carrier belts and the rolls 19 (Fig. 2) their flaps are turned up and "broken" on their crease lines by those portions of the twisted belts 14 running over the backing strips 70. Said strips properly support the belts against the resistance offered by the stiffest kind of material employed in paper box making, and the belts therefore act continuously to gradually break and then fold the blanks, no gap or interruption occurring as is the case where stationary rods or inclines do the first breaking. At the same time, the adjustment of the swinging arms described provides for all characters of blanks as well as can be done with adjustable rods which latter cause objectionable friction tending to cause the blanks to turn or get askew.

By the time each blank passes the last of the rolls 78 (Figs. 1 and 4) it is completely folded by the belts. From the rolls 78 to the pulleys 45 the belts 44 incline up-

- ward slightly, the degree of inclination being varied by adjusting the bearings for the shafts of said pulleys as hereinbefore explained in connection with Figure 5.
- 5 This relieves the pressure on the blanks so that as each blank passes to the faster-travelling belts 82, 83, its speed of travel will be increased. The reason for employing speed belts 82, 83, is that many kinds of 10 box blanks have rearwardly and forwardly extending flaps which are later to be used for closing in the ends of the boxes when set up and filled. As the blanks leave the folding belts 44 in flat folded condition and 15 closely following one another, the projecting flaps referred to overlap and this, if not overcome, would interfere with the operation of the stacker to which the flat folded boxes are delivered by the speed 20 belts 83, 84. Such a stacker is illustrated in our application filed April 6, 1921, Serial No. 459,134. The speed belts act to separate or draw the folded boxes apart far enough so that their forward and rearward 25 flaps will not overlap when they reach the stacker and so interfere with their orderly arrangement in a row thereon. It is to aid in attaining this result that the bearings for the shafts of the pulleys 45 are adjust- 30 able, so that, no matter what may be the thickness of the blank material, the belts 44 at their delivery ends will not hold the folded blanks tightly but only with sufficient pressure to frictionally feed them to 35 the speed belts. The pressure required on the edges or folded margins to remove any tendency of the overlapped glued portions to spring apart is effected by the rolls 109, 111, as hereinbefore described.
- 40 To aid in ensuring straight travel of the folded boxes while passing from the belts 27, 44, to the speed belts 82, 83, one of the guide bars 25 is extended (see Fig. 4) past the receiving ends of said speed belts.
- 45 As shown by comparing Fig. 1 (which shows the left-hand carrier and folder belts) with Fig. 4, one of the frame castings 22 is longer than the other, and its pulley for the delivery end of the folder belt is so 50 located, as to substantially lap by the speed belts, thereby aiding in keeping control of the folded boxes as they pass to the speed belts since there is no gap past which the momentum of the boxes is relied upon to 55 ensure their passage.
- Having now described our invention, we claim:
1. A folding machine having a pair of blank-folding belts and pulleys for the ends 60 of said belts, the pulleys for those ends of the belts which first act on the blanks being laterally and vertically adjustable independently of the pulleys at the other ends of the belts.
- 65 2. A folding machine having a pair of

blank-folding belts, laterally adjustable pulleys for those ends of the belts which first act on the blanks, and means for varying the inclination of the axes of rotation of said pulleys.

3. A folding machine having a pair of twisted blank-folding belts, laterally adjustable pulleys for those ends of the belts which first act on the blanks, and means for varying the inclination of the axes of 70 rotation of said pulleys to vary the twist of the belts.

4. A folding machine having a blank folding belt, a pivoted arm carrying a pulley for the end of the belt which first acts on the blanks, and means for securing said arm in more or less outwardly swung position.

5. A folding machine having a blank folding belt, a pivoted arm carrying a pulley for the end of the belt which first acts on the blanks, and means for securing said arm in more or less outwardly swung position, said arm having means including a spring to yieldingly increase the distance of 80 the pulley from the pivot of the arm.

6. A folding machine having a twisted blank-folding belt, a backing strip for that portion of the belt which first acts on the blanks, and means for varying the degree 85 of twist of both the belt and said strip.

7. A folding machine having a twisted blank-folding belt, a pivotally adjustable arm carrying a pulley for the end of the belt which first acts on the blanks, and a 100 backing strip carried by said arm to support the belt.

8. A folding machine having a pair of twisted blank-folding belts, a pair of pivoted arms carrying pulleys for the ends of the belts which first act on the blanks, means for adjusting said arms vertically and means for securing said arms in more or less outward 105 swung positions.

9. A folding machine having a pair of 110 twisted blank-folding belts, a pair of pivoted arms carrying pulleys for the ends of the belts which first act on the blanks, means for adjusting said arms vertically, means for securing said arms in more or less outward 115 swung positions, and belt-backing strips carried by said arms.

10. A folding machine having a twisted blank-folding belt, a laterally and vertically adjustable pulley for that end of the belt which first acts on the blanks, and a vertically adjustable guiding pulley located at an intermediate point of the operative stretch of said belt.

11. A folding machine having a twisted blank-folding belt, a laterally and vertically adjustable pulley for that end of the belt which first acts on the blanks, and a vertically adjustable guiding pulley located at an intermediate point of the operative stretch 125 130

of said belt, means being provided for rotating said intermediate pulley on an axis more or less inclined from the vertical.

12. A folding machine having a pair of carrier belts, a series of pressure rolls above said belts and extending part way of the length thereof, a pair of twisted folder belts extending past said rolls, and means for adjusting the folder belts to cause those portions thereof which are beside the pressure rolls to travel more or less laterally inclined relatively to said carrier belts and pressure rolls.

13. A folding machine having a pair of carrier belts, a series of pressure rolls above said belts and extending part way of the length thereof, a pair of twisted folder belts extending past said rolls, and means for adjusting the folder belts to cause those portions thereof which are beside the pressure rolls to travel more or less laterally inclined relatively to said carrier belts and pressure rolls, said adjusting means comprising pivotally supported arms carrying pulleys for the folder belts, and means for securing said arms in outwardly swung positions.

14. A folding machine having two belt-carrying frames provided with inwardly extending shafts having pulleys for the belts, a clear space being provided between the pulleys of the two frames to enable the belts to be slipped off from the pulleys and removed.

15. A folding machine having two belt-carrying frames provided with inwardly extending shafts having pulleys for the belts, a clear space being provided between the pulleys of the two frames to enable the belts to be slipped off from the pulleys and removed, means being provided to enable the two frames to be laterally adjusted to bring the belts of the two frames into close relationship.

16. A folding machine having two frame bars, carrier belts supported by said bars, a pair of folder belts, and pulley supports for the delivery ends of the folder belts, said supports being connected to and extending above said frame bars, each of said supports having an independent inwardly projecting shaft for its pulley.

17. A folding machine having two frame bars, carrier belts supported by said bars, a pair of folder belts, and pulley supports for the delivery ends of the folder belts, said supports being connected to and extending above said frame bars, each of said supports having an independent inwardly projecting shaft for its pulley, means being provided for driving the pulleys carried by said supports.

18. A folding machine having two frame bars, carrier belts supported by said bars, a pair of folder belts, and pulley supports

for the delivery ends of the folder belts, 65 said supports being connected to and extending above said frame bars, one of said supports being constructed to sustain its pulley at a point in advance of the other pulley.

19. A folding machine having a pair of carrier belts and a pair of folder belts, driving means acting on the return stretches of the carrier belts, and means for driving the pulleys on which the folder belts are mounted at their delivery ends.

20. A folding machine having a pair of carrier belts, a pair of wheels engaging opposite surfaces of the return stretch of each of said belts, means for causing said wheels 80 to yieldingly pinch the belts, and means for driving said wheels.

21. A folding machine having a pair of carrier belts, a pair of wheels engaging opposite surfaces of the return stretch of each 85 of said belts, an elbow lever for supporting one wheel of each pair, a spring for actuating said lever to cause its wheel to bear yieldingly against the belt, and means for driving said wheels.

22. A box-folding machine having carrier belts, folder belts portions of which at the delivery ends are above the carrier belts, pulleys for said belts relatively arranged to cause the carrier and folder belts to diverge 95 at their delivery ends, and means for drawing the folded boxes away from said belts when they reach said diverging portions.

23. A box-folding machine having carrier belts, folder belts portions of which at the delivery ends are above the carrier belts, pulleys for said belts relatively arranged to cause the carrier and folder belts to diverge at their delivery ends, and higher speed belts for drawing the folded boxes away 100 from the diverging portions of the carrier and folder belts.

24. A box-folding machine having carrier belts, folder belts portions of which at the delivery ends are above the carrier belts, pulleys for said belts relatively arranged to cause the carrier and folder belts to diverge at their delivery ends, means for adjusting the pulleys of the folder belts to vary the degree of divergence, and means for drawing the folded boxes away from said belts 110 when they reach said diverging portions.

25. A folding machine having carrier belts and folder belts and speed belts to which the folded articles are delivered, said belts being relatively arranged to extend past each other to keep control of the folded articles as they pass to the speed belts.

26. In a machine of the character described, means for compressing the folded margins of blanks, said means comprising a roll of uniform diameter, a shaft parallel therewith, a pair of sleeve rolls on said

shaft each sleeve roll having an annular groove, a rod parallel with said shaft, and yokes fitting the said grooves and having hubs adjustable on said rod.

5 27. A folding machine having a pair of carrier belts and a pair of cooperating twisted folding belts, and guides for the outer edges of said belts, the folding belts being bevelled along the edges which, during a portion of their travel, are close to the carrier belts and guides.

10 28. A folding machine having a pair of carrier belts and a pair of cooperating twisted folding belts, and guides for the

outer edges of said belts, the corners of the 15 folding belts where their outer edges and inner surfaces meet being cut away.

29. A machine of the character described having folding instrumentalities and belts to which the articles folded are delivered by 20 said instrumentalities, said machine having a side guide for the said articles extending past the receiving ends of said belts.

In testimony whereof we have affixed our signatures.

LEON E. LA BOMBARD.
